PUTLOG SUPPORT

Wilhelm Krasin, Marshfield, Wis.

Application July 2, 1937, Serial No. 151,738
Renewed March 9, 1939

3 Claims. (Cl. 304—32)

By way of explanation, it may be stated that, when it is desired to mount a scaffold beam or "putlog" on a masonry wall, it has been the practice heretofore to leave an opening in the wall, to form a shoulder upon which one end of the beam may rest. Such an operation leaves a hole in the wall, to be filled later, causing patch-work which is unsightly.

The present invention aims to provide a novel support for the scaffold beam, the construction being such that the support may be introduced into the mortar between courses, it being possible to remove the support, when the occasion for the use thereof has passed.

15 The invention aims, further, to provide novel means whereby the beam may be held on the support, and to supply novel means whereby the support will be held, by a mortar clinch, in the wall.

20 It is within the province of the disclosure to improve generally and to enhance the utility of devices of that type to which the present invention appertains.

With the above and other objects in view, which 25 will appear as the description proceeds, the invention resides in the combination and arrangement of parts and in the details of construction hereinafter described and claimed, it being understood that changes in the precise embodiment 30 of the invention herein disclosed, may be made within the scope of what is claimed, without departing from the spirit of the invention.

In the accompanying drawings:

Fig. 1 shows in side elevation, a device embodying the invention, assembled with a masonry wall and with the scaffold beam;

Fig. 2 is a vertical longitudinal section taken through the device forming the subject matter of this application, a portion of the beam and a 40 portion of the wall being shown in section;

Fig. 3 is a transverse section on the line 3—3 of Fig. 2;

Fig. 4 is a perspective illustrating the device per se;

45 Fig. 5 is a transverse section showing a slight modification;

Fig. 6 is a perspective showing a modified form of the invention;

Fig. 7 is a plan of the blank out of which the 50 device shown in Fig. 6 is formed;

Fig. 8 is a longitudinal section of the device depicted in Fig. 6;

Fig. 9 is a perspective showing a modification;

Fig. 10 is a plan of the blank out of which the 55 device delineated in Fig. 9 is made;

Fig. 11 is a longitudinal section of the article appearing in Fig. 9;

Fig. 12 is a longitudinal section showing a slight modification in the form illustrated in Fig. 9.

In carrying out the invention as disclosed in 5 Figs. 1 to 4, there is provided a support including an elongated plate 1 made of sheet metal of sufficient strength to support the beam of a scaffold. At its inner end, the plate 1 is tapered as shown at 2, so that it may be introduced readily into the 10 mortar 3 between the courses 4 of a masonry wall 5. In the tapered portion 2 of the plate 1 there is an opening 12, of sufficient size so that the mortar may engage in the opening, as shown at 14, thereby affording a temporary mortar 15 clinch for holding the plate in place, the tapering of the plate, at 2, facilitating the introduction of the plate into the mortar 3.

At the outer end of the plate 3 is located an 20 upstanding, loop-shaped member, having an opening 15 of sufficient size to receive the beam or putlog 16 of a scaffold, the upstanding member being designated as a whole by the numeral 6. The upstanding member 6 has flanges 7 extended underneath the plate 1 and terminating closely 25 adjacent to the longitudinal edges of the plate, the flanges 7 being secured to the plate by any suitable means, such as spot welding. If desired, the structure shown in Fig. 5 may be used, and therein the upstanding member 9 has its flanges 30 8 secured at their ends, as shown at 11, by welding or otherwise, to the plate 10.

The beam 16 is inserted into the opening 15 of the loop-shaped member 6 and, in order to hold the beam against shifting endwise, securing elements 17 may be inserted into the beam 16, through openings 18 in the plate 1. The openings 18 are somewhat smaller than the opening 12, and are located between the tapered portion 2 of the plate and the upstanding loop-shaped 40 member 6.

It will be obvious that the device may be used to support the beam 16, without leaving large holes in the wall 5. When the occasion for the use of the device has passed, it may be pulled 45 out readily, and only a little pointing is necessary in order to close the opening in the mortar 3, formerly occupied by the inner end of the plate 1.

The tapered end 2 of the plate 1 of one support may be inserted through the loop-shaped 50 member 6 of another plate, and in this way, a plurality of the devices under discussion may be stacked in small compass, for transportation.

In Figs. 6, 7 and 8, the plate is marked by the numeral 19 and has a tapered inner end 20, in 55

which is formed a hole 21 for the mortar clinch. The holes for the securing elements 17 of Fig. 2 are designated by the numeral 22.

At its outer end, the plate 19 has a widened head 23 in which is formed an I-shaped slot 24, including a body 25 and extensions 26 at the ends of the body of the slot, the extensions being arranged at right angles to the body of the slot.

The head 23 of the plate is bent upwardly 10 along the lines 27 at the rear ends of the extensions 26 of the slot 24, to form the side arms 28 of a loop-shaped member having an opening 29 for the reception of the scaffold beam. The end of the head 23 is bent along lines 30, located at 15 the forward ends of the extensions 26 of the slot 24, to form a forwardly projecting wing 31, and to form a rearwardly extended wing 32, the wings being located in the same plane, parallel to the plate 19. When the plate is turned up 20 along the lines 27, to form the side arms 28, the part of the plate that is immediately behind the body 25 of the slot 24 remains in the same plane with the plate, to form a forwardly projecting tongue 33, located below the wing 31, 25 in parallel relation thereto.

In the form shown in Fig. 9, the blank of Fig. 10 is used. The plate 34 has a tapered rear end 35, supplied with a large hole 36, to produce a mortar clinch. The holes for the securing elements are marked by the numeral 37. The broadened head of the plate is designated by the numeral 38 and has a rectangular opening 39. The head 38 may be turned up along the rear edge of the opening 39, to form a loop-shaped member 40, the opening 39 being available for 30 the reception of one end of a beam.

In Fig. 12, parts hereinbefore described in connection with Figs. 9, 10 and 11 are designated by numerals previously used, with the suffix "a". The modification of Fig. 12 consists 40 in bending the upper part of the member 40a to form a wing 41, which, like the wing 32 of Fig. 6, overlaps the beam.

In any of its forms, the device is simple in construction but will be found thoroughly advantageous for the ends in view.

If desired, the structure shown in Fig. 7 may be sold as an article of manufacture, the purchaser being left free to do the bending which produces the article shown in Fig. 6. 5

Having thus described the invention, what is claimed is:

1. A device for supporting a scaffold beam on 10 a masonry wall, comprising a flat plate provided at its outer end with an integral upstanding member having a beam-receiving opening, the inner end of the plate being tapered for ready introduction into mortar, the tapered portion of 15 the plate being provided with a first opening large enough to afford a temporary mortar clinch for the plate, the plate being provided with a smaller opening for the reception of a beam-engaging supporting element, the smaller opening 20 being located between the upstanding member and the tapered portion of the plate.

2. A device for supporting a scaffold beam on a masonry wall, comprising a plate provided at 25 its outer end with an upstanding member having a beam-receiving opening, the upstanding member being provided with forwardly and rearwardly extended wings located at the upper edge of the opening and disposed approximately parallel to the plate, the plate being provided 30 with a forwardly extended tongue prolonged beneath the forwardly extended wing, in approximately parallel relation thereto.

3. In a device of the class described, a plate having a tapered inner end for introduction into 35 mortar, the plate being provided near to its outer end with an I-shaped slot including a body disposed transversely of the length of the plate, the slot including end extensions located approximately parallel to the length of the plate. 40
